UNITED STATES PATENT OFFICE.

CHARLES HAMMER, OF HOLLIS COURT BOULEVARD, NEW YORK.

METAL CAP.

Application filed November 9, 1922. Serial No. 599,758.

To all whom it may concern:

Be it known that I, CHARLES HAMMER, a citizen of the United States, residing at Hollis Court Boulevard, in the county of 5 Queens and State of New York, have invented certain new and useful Improvements in Metal Caps, of which the following is a specification.

This invention relates to closures particu-

10 larly adapted for glass containers, such as jars or bottles, the object of the invention being to provide an improved metal cap which may be readily made of thin sheet metal having a reinforced flange or skirt

15 provided at the lower edge thereof with in- struck locking projections or lugs adapted to engage the external threads or pro- jections of a glass container, whereby the cap may be readily applied to seal

20 the container and readily removed, and in which the cap flange will lie close to the glass container, the present invention being an improvement in part on my prior Patent No. 1,079,238 dated November 18, 1913.

25 In that patent the skirt or flange is pro- vided with a curled, beaded or rolled edge of hollow form which, when flattened to form the projections, results in a part there- of projecting beyond the outer wall of the

30 flange or skirt, while at the same time the formation of the locking lugs in the manner described in said patent somewhat breaks the circular contour of the skirt. Moreover, in that patent the skirt above its lower edge

35 is at no point of double thickness of metal, whereas in the present improved cap the skirt itself is not only of a double thickness of metal, but the formation of the locking lugs does not so appreciably break the circular

40 contour of the skirt so that the lower edge of the skirt has a less bulky appearance, and the cap flange will be closer to the neck of the glass container, while at the same time the lower edge is so formed that it will not 45 cut the hands of the user nor be liable to corrosion.

In the drawings accompanying and forming a part of this specification, Fig. 1 is a side view of this improved cap; Fig. 2 is 50 a bottom view thereof; Fig. 3 is a cross section taken on line 3—3 of Fig. 1; and Fig. 4 is a detail view of a modification.

Similar characters of reference indicate corresponding parts in the several views of 55 the drawings.

In the manufacture of this improved cap,

a flat sheet metal blank of relatively thin material is first pressed or stamped into the form of a hat-shaped blank, that is, a blank having a top 2 and a skirt or flange 3. The 60 flange or skirt of the blank is preferably provided with an out-turned portion or edge, although this may be inturned if desired, and this out-turned or inturned portion of the flange or skirt is pressed or 65 rolled into position preferably on the outside, so as to hug the flange or skirt as at 5 of the cap, thereby forming what may be designated as a hemmed edge or flange 6. In practice this reinforcing portion or edge 70 will extend the desired distance upwardly of the flange or skirt, thereby to the extent of its height, providing a double thickness of wall around the entire skirt or flange. 75

The skirt or flange is then roughened, as by providing it with corrugations 7, which not only strengthen the cap, but facilitate its assemblage on the jar as well as its removal therefrom, and these corrugations in one form of cap shown herein (Figs. 1 to 3) are formed in the double wall of the skirt while in another form (Fig. 4) thereof, it will be observed that the reinforcing wall of the cap stops just short of the corruga- 80 tions. 85

Then, by means of the proper pressure at spaced intervals around the lower edge of the cap, suitable locking projections or lugs 8 are formed from the double thickness wall of the flange or skirt, these projections or 90 lugs extending inward radially of the cap and in such manner that the circular contour of the flange at the outside is not es- 95 sentially departed from. In the present im- proved cap these projections are shown in the form of relatively short lugs as distin- guished from wedge-shaped projections or threads, such as is shown in my contemporaneously pending application Serial No. 598,078, filed October 31, 1922, in conse- 100 quence of which the hemmed edge or flange may also be corrugated, which it could not be in a cap having threads or wedge-shaped projections formed in such hemmed edge. As shown these lugs, relatively short circum- ferentially of the cap, have substantially flat or horizontal locking faces. 105

As a result of this construction, a metal cap is produced having what may be prop- erly designated as a closed flat beaded edge 110 and flange and closed inwardly projecting locking lugs, thus having no raw lower edge

to be attacked by acid and moisture, nor to cut the hands of the user, and in which the general circular contour of the flange is not appreciably departed from, while at the same time the locking projections or lugs are of double thickness of metal, which double thickness of metal extends partially up the side wall of the flange or skirt, so that it likewise is reinforced, thereby strengthening the locking projections as well as the flange in addition to the strength which is given to these parts by the corrugations, so that the cap is strong and durable and is sufficiently rigid to withstand all of the pressure and strains falling thereon, and will meet all the requirements of a practical and commercial metal cap, and take up the necessary variations in glass jars or containers, especially since the formation of the lower edge in the manner described herein enables the cap flange to be closer to the container threads, whether the flange be straight or have a slight outward flare at its lower edge, than is usually possible with a hollow beaded or curled edge, so that with the same size of lugs greater variation may be taken up in the container than has heretofore been practicable or where this is not necessary the lugs may have less inward projection to accomplish the same result, while at the same time it is neat and ornamental.

It will be observed that by reason of the reinforcing double wall of the cap flange which in a shallow flanged cap is shown extending substantially half way up the depth of the flange and formed by a single bend of the flange at its lower edge, the locking lugs are stiffened so as to prevent the flange of the cap from being distorted in the drawing action on the container to such an extent as to cause the top to buckle and the cap to be bent to any degree out of shape. In fact, the double wall thickness of the flange very materially prevents the bending of the cap out of shape, while enabling it however, to conform to any ordinary distortion or variation of the glass container or its projections or threads, and to be made of relatively thin sheet metal.

Thus, I have provided what may be properly designated as a hemmed edge cap having locking lugs formed from such hemmed edge, and which hemmed edge in one form thereof is also provided with strengthening corrugations, as a result of which the formation of the locking projections does not cause the flange of the cap to materially depart from its circular formation, and in which cap the flange or skirt is relatively shallow, as distinguished from what is known as a Mason jar cap, in which the flange is very deep, so that in this improved cap the locking lugs may engage the projections or lugs of the glass container relatively close to the top thereof.

In practice, a suitable form of liner is usually used within the cap to effect an hermetic seal of the glass container.

In the form of cap shown in Fig. 4, the corrugations may be somewhat shorter in a shallow flange cap, and terminate short of the hemmed edge, and which, when they are outstruck, will thus more effectively break the appearance of this edge.

It will be understood that by describing in detail herein any particular form, structure or arrangement, it is not intended to limit the invention beyond the terms of the several claims or the requirements of the prior art, since I believe I am the first to provide a cap with a reinforcing hemmed edge having locking lugs formed thereof, as well as a cap in which the hemmed edge is provided with corrugations.

I claim as my invention:

1. A metal cap formed of relatively thin sheet metal comprising a top and a depending skirt bent upwardly upon itself at its lower edge to closely hug said skirt and form a reinforced hemmed flange, the lower double edge of the skirt being bent radially inward at intervals to form short double parallel walled relatively flat locking lugs, the double parallel walls of the lugs providing increased resistance to distortion thereof and to the buckling of the cap top during the drawing down of the cap on to the container, and permitting the cap to be made of relatively thin sheet metal, the inner bent edges of the parallel walled lugs having a rounded formation adapted to retain the lacquer and avoid a too sharp edge, and the said closely hugging portion extending a material distance above the plane of the points of junction of the lugs and the skirt.

2. A metal cap having a double walled depending skirt with corrugations, and inwardly extending locking projections formed from said double wall.

3. A metal cap formed of relatively thin sheet metal having a depending skirt provided with a hemmed edge formed by bending the metal at the lower edge of the skirt upon itself, said hemmed portion being forced inwardly at intervals to form locking projections and pressed to form corrugations therein.

4. A metal cap formed of relatively thin sheet metal having a depending skirt provided with a hemmed edge formed by bending the metal at the lower edge of the skirt outwardly upon itself, said hemmed portion being forced inwardly at intervals to form locking projections and pressed to form corrugations therein.

5. A metal cap having a depending skirt bent at its lower edge upwardly upon itself to closely hug said skirt thereby forming a double wall or hemmed edge, said skirt having corrugations in the double wall there-

- of, and also having below the same a plurality of inwardly extending locking projections.
6. A metal cap of relatively thin sheet metal having a shallow depending double-walled skirt having double walled corrugations, and double walled inwardly extending locking projections.
7. A metal cap having a double walled skirt provided with double walled substantially closed inwardly projecting lugs having relatively flat horizontal holding faces, and also provided with reinforcing corrugations in said double wall.
8. The method of making a sheet metal cap of relatively thin metal, which consists in pressing a flat blank into shape to form a top and a depending skirt, then subjecting the flange or skirt to pressure thereby to bend the lower edge thereof upon itself so as to substantially hug the skirt for a distance upward thereof to form a double wall, and then subjecting the skirt to pressure to provide such double wall with corrugations and instruck locking projections. 15 20 25

Signed at Brooklyn, N. Y., this 2nd day of November, 1922.

CHARLES HAMMER.
